Mamie M. Garland
By Walter M. Fuller, Atty.

UNITED STATES PATENT OFFICE.

MAMIE MATHER GARLAND, OF CHICAGO, ILLINOIS, ASSIGNOR TO GARLAND VENTILATOR COMPANY, OF CHICAGO, ILLINOIS, A CORPORATION OF ILLINOIS.

VENTILATOR.

Application filed June 7, 1926. Serial No. 114,096.

My invention relates to ventilators, and similar appliances, and pertains more particularly to devices of this character for use on the roofs of vehicles, whereby the 5 pure air is withdrawn from the vehicle by the ventilator, the latter being constructed with a view to performing this function with efficiency and in such a manner that rain, snow, dirt and the like may not find an inward passage therethrough to the inside of the vehicle.

The currents of air flowing by the ventilator are used to advantage by reason of the peculiarities of its construction to abstract or withdraw the foul or contaminated 15 air with facility and effectiveness, this action being aided by employing side openings, heretofore used only as drains, to perform also an air-withdrawal function thereby materially increasing the power and action of 20 the ventilator as a whole.

To enable those skilled in this art to have a full and complete understanding of this invention, both from structural and functional standpoints, in the accompanying drawing, forming a part of this specification, a present desirable and preferred embodiment has been illustrated and described, the 25 same parts being supplied with like reference characters throughout the several views of such drawing.

In this drawing:

Figure 1 is a central longitudinal vertical section through the improved ventilator on 30 line 1—1 of Figure 2;

Figure 2 is a plan view of the ventilator partly broken away to more clearly indicate some of its internal construction; and

Figure 3 is a cross section through the 35 ventilator on line 3—3 of Figure 2.

By reference to this drawing, it will be perceived that the novel and improved structure, which is desirably made of sheet-metal properly coated against corrosion by the elements, includes a base-plate 11 having a central round hole 12 therethrough of substantial size around the margin or border of which the metal of the base-plate has been turned up to provide a round or circular flange 13, the ventilator being intended to be mounted flatwise on top of the roof 14 of a vehicle such as a railway or street car, bus, automobile, or the like, with the hole 12

in register with a ventilating aperture 15 through the roof. 55

Along its two side edges, this base or bottom-plate 11 has parallel upstanding side-walls 16, 16 co-extensive in length with such bottom-plate.

In actual practice, it is convenient to form 60 such side-walls by merely bending up parts of the base-plate leaving outstanding sections or flanges 17, 17 of double metal thickness secured to the top of the roof by means of screws 18, 18, the top margins of the side-walls being outstanding as at 19, 19. 65

A cover or roof-plate 21, parallel to the floor or base-plate 11, is secured to these flanges 19, 19 by having its marginal sections bent around them as indicated in Figure 3, but this top plate is of less length than the base and side-walls, as shown in Figure 1, and has its front and rear edges sloped or inclined downwardly in opposite directions at 22, 22 between the side-walls 16, 16 the 75 lower edges of such flanges being finished by folding the metal back upon itself, as is common sheet-metal practice. 70

Upright cross-walls 23, 23 extending from the base-plate to the cover-plate are fastened 80 in position to the former by foot flanges 24, 24, these walls being located just outside of opposite portions of the circular flange 13, and, may, if desired, be curved slightly at their central sections to conform to the shape 85 of such flange.

As is clearly depicted in Figures 2 and 3, these transverse walls do not extend across the full width of the appliance, but leave substantial spaces or gaps between their ends 90 and the side-walls.

At each end of the structure an air-deflecting end-wall 25 is provided and secured in position in any convenient manner, and, in the present instance, these walls are indicated as somewhat concave in cross-section, although their shape and degree of or lack of inclination are matters which can be varied considerably. 95

In the instant case, the lower edges of such sheet-metal end-walls are folded or bent around the ends of the bottom-plate and they also have ears or lugs 26 fastened to the inner faces of the side-walls. 100

The top margins of such end-walls, finished smooth by folding back the metal, are 105

located above the lower edges of the top or cover flanges 22, 22, but are positioned below the upper face of such top-plate, all as is clearly shown in Figure 1, a substantial gap 5 being present between each such end-wall and its companion or correlated top-plate inclined flange.

Each side-wall, just above the bottom-plate, is supplied with a plurality of drain holes 27, 27, each such wall having four in 10 the present instance, and those two of each such four opposite the space between the cross-walls 23, 23 are provided at their opposite ends with outstanding, aid-deflecting 15 wings or lugs 28, 28, the presence of which in no way lessens the capacity of such apertures for acting as drain holes but they materially increase the amount of foul air withdrawn from the vehicle by reason of the 20 withdrawal suction action of the air striking and being deflected by such wings on the air inside of the ventilator.

When the vehicle, equipped with such improved ventilator, is traveling forward, the 25 air striking the front end-wall 25 is swerved or deflected upwardly and upon reaching the top edge of such end-wall, it flows over it and over the top of the upper wall 21, in so doing forming a substantial suction-action 30 at the space between the parts 25 and 22 which withdraws the foul air from the vehicle through the roof aperture 15, hole 12, the space between the cross-walls, the gaps 35 between the ends of the cross-walls and the side-walls and the space beneath the overhanging portion of the top-wall.

Such withdrawal operation is aided by the 40 upward inclination of the flange 22 which assures that the air currents will easily pass over the top of the roof-plate 21.

Also, the air flowing rearwardly over the top-plate 21 causes a similar suction action as it passes over the rear cross-opening between the parts 22 and 25, thus effecting a 45 material removal of foul air at that end of the appliance.

This whole air abstraction action, however, is increased in positive degree by the 50 suction-action which occurs at those of the side-openings 27 fitted with the deflectors 28 which augment the withdrawal action through such openings.

As will be readily understood, any rain 55 which may have access to the interior of the structure cannot find its way into the vehicle, being blocked by the guarding flange 13 around the opening 12 and it has quick egress or discharge through the drain openings in the side-walls.

Those skilled in this art will readily understand that this invention is not limited 60 and restricted to the precise and exact details shown and described and that many minor mechanical changes may be incor- 65 porated in the appliance without departure

from the heart and essence of the invention as defined by the appended claims and without the sacrifice of any of its substantial and material benefits and advantages.

I claim:

1. In a ventilator, the combination of a base having an opening to coincide with a similar aperture through the roof of the structure to be ventilated and an upstanding flange around the margin of said opening, 70 side-walls rising from said base, a top-wall of less length than and connecting said side-walls with a space between the under side of said top-wall and the top edge of said flange, intermediate transverse walls to the front 80 and rear of said base opening extending from said base to said top-wall but terminating short of said side-walls and located inwardly away from the front and rear margins of said top-wall, and end-walls upstanding from the front and rear ends of said base with spaces between them and said top-wall, said side-walls just above said base having drain holes therethrough with outstanding lips at their ends to direct the outside 85 currents of air to increase the suction at said drain holes.

2. In a ventilator, the combination of a base having an opening adapted to coincide with a similar aperture through the roof of 90 the structure to be ventilated and an upstanding flange around the margin of said opening, side-walls rising from said base, a top-wall of less length than and connecting said side-walls with a space between the under side of said top-wall and the top edge of 95 said flange, intermediate transverse walls to the front and rear of said base opening extending from said base to said top-wall but terminating short of said side-walls and located inwardly away from the front and rear margins of said top-wall, said front and rear margins having turned-down flanges between said side-walls and end-walls upstanding from the front and rear ends of said base 100 with spaces between them and said top-wall, said side-walls just above said base having drain holes therethrough with outstanding lips at their ends to direct the outside currents of air to increase the suction at said 105 drain holes.

3. In a ventilator, the combination of a base having an opening adapted to coincide with a similar aperture through the roof of the structure to be ventilated and an upstanding flange around the margin of said opening, side-walls rising from said base, a top-wall of less length than and connecting said side-walls with a space between the under side of said top-wall and the top edge 110 of said flange, intermediate transverse walls to the front and rear of said base opening extending from said base to said top-wall but terminating short of said side-walls and located inwardly away from the front and rear margins of said top-wall, said front and rear margins having turned-down flanges between 115 said side-walls and end-walls upstanding from the front and rear ends of said base with spaces between them and said top-wall, said side-walls just above said base having drain holes therethrough with outstanding lips at their ends to direct the outside currents of air to increase the suction at said drain holes.

rear margins of said top-wall, said front and rear top-wall margins having downwardly-sloping flanges between said side-walls, and end-walls upstanding from the front and rear 5 ends of said base with spaces between them and said top wall, the top edges of said end-walls being above the lower margins of said top-wall flanges, said side-walls just above

said base having drain holes therethrough with outstanding lips at their ends to direct 10 the outside currents of air to increase the suction at said drain holes.

In witness whereof I have hereunto set my hand.

MAMIE MATHER GARLAND.
